Primary Examiner — Paula Allen Greene(74) *Attorney, Agent, or Firm* — Myers Wolin, LLC(57) **CLAIM**

The ornamental design for a headphone, as shown and described.

DESCRIPTION

FIG. 1 is a perspective view of one embodiment of a headphone showing my new design;
FIG. 2 is a front elevation view thereof;
FIG. 3 is a rear elevation view thereof;
FIG. 4 is a right side elevation view thereof, the left side elevation view being a mirror-image thereof;
FIG. 5 is a top view thereof;
FIG. 6 is a bottom view thereof;
FIG. 7 is a front view in an alternate folding configuration;
FIG. 8 is a perspective view of an alternative embodiment of a headphone showing my new design;
FIG. 9 is a front elevation view thereof;
FIG. 10 is a rear elevation view thereof;
FIG. 11 is a right side elevation view thereof, the left side elevation view being a mirror-image thereof;
FIG. 12 is a top view thereof;
FIG. 13 is a bottom view thereof; and,
FIG. 14 is a front view in an alternate folding configuration. The broken lines are for illustrative purposes only and form no part of the claimed design.
